UNITED STATES PATENT OFFICE.

AUGUST J. FREY, OF BROOKLYN, NEW YORK.

FLEXIBLE-TUBING COMPRESSOR.

1,359,980.

Specification of Letters Patent. Patented Nov. 23, 1920.

Application filed January 27, 1920. Serial No. 354,404.

To all whom it may concern:

Be it known that I, AUGUST J. FREY, a citizen of the United States, and resident of the borough of Brooklyn, in the city and State of New York, have invented a new and useful Improvement in Flexible-Tubing Compressors, of which the following is a specification.

The object of my invention is to provide certain improvements in the construction, form and arrangement of the several parts of a flexible tubing compressor whereby the compressor may be effectively used with tubing of different sizes and having walls of varying thicknesses and in which the parts are made very strong and light.

A further object is to provide a device of the above character in which the action is very powerful and the friction is materially reduced between the lever and the movable jaw.

A practical embodiment of my invention is represented in the accompanying drawings, in which,

25 Fig. 1 represents my compressor in top plan applied to a flexible tubing, the jaws being closed.

Fig. 2 represents a longitudinal section taken in the plane of the line II—II of 30 Fig. 1.

Fig. 3 represents a horizontal section taken in the plane of the line III—III of Fig. 2.

Fig. 4 represents a transverse section taken 35 in the plane of the line IV—IV of Fig. 2.

Fig. 5 represents the compressor in side elevation, the jaws being open, and

Fig. 6 represents a bottom plan view of the compressor.

40 The compressor comprises a sheet metal body portion developed into a fixed jaw 1 and a movable jaw 2 connected by a spring portion 3, tending to hold the jaws open. The fixed jaw 1 is provided with side ears 4 which extend upwardly beyond the movable jaw 2.

The compressing lever 5 may be made of sheet metal and it is provided with side lugs 6 which enter recesses 7 in the side ears 4 of the fixed jaw for hinging the compressing lever to the said ears. This compressing lever is provided with depending side flanges 8, the forward ends of which bear against the movable jaw 2. The relationship of the bearing points of the flanges 8 to the hinge

lugs 6 is such that when the lever is swung into one position, the jaws of the compressor are permitted to open and, when the lever is swung into another position the jaws are closed. The compressing lever is developed into a loop 9 between the flanges 8 and the hinge lugs 6, so that when the lever is swung to close the jaws it may yield slightly to compensate for tubing walls of varying thicknesses. 60

The fixed jaw 1 is provided with crossed stiffening ribs 10 at the base of the uprising ears 4 opposite the bearing points of the flanges of the compressing lever so as to materially strengthen the fixed jaw at this 65 point.

The movable jaw is provided with longitudinally arranged stiffening ribs 11 forming grooves 12 for guiding the bearing points of the flanges 8 of the compressing lever in 70 their travel along the jaw.

The front edges of the ears 4 are recessed, as shown at 13, so that when the flexible tubing is compressed between the transverse lips 14 and 15 of the fixed and movable jaws, 80 the tubing will have more space to spread laterally. This is especially desirable where the compressor is used with large tubing.

The bearing points of the flanges 8 are preferably rounded as shown to give a 85 smooth action with a minimum amount of friction when the compressing lever is swung to its different positions to open or close the jaws.

It will be seen that by locating the hinged connection between the compressing lever and the ears of the fixed jaw at a distance back of the bearing points of the flanges and by providing the loop 9 between the hinged connection and the bearing points, a slight 90 yielding action is obtained which is very valuable in insuring the proper closure of the flexible tubing without danger of straining or distorting the working parts of the compressor. It will furthermore be seen 95 that by providing the jaws with strengthening ribs, the jaws are prevented from bending when strain is placed thereon and a more efficient compressor is thereby obtained. 100

105 It is evident that various changes may be made in the construction, form and arrangement of the several parts without departing from the spirit and scope of my invention; hence I do not wish to limit myself to 110

the particular embodiment herein shown and described, but—

What I claim is:

1. A flexible tubing compressor comprising fixed and movable jaws and a compressing lever constructed to yield slightly when swung into position to close the jaws.
2. A flexible tubing compressor comprising a sheet metal body portion developed into fixed and movable jaws, the fixed jaw having uprising ears, and a compressing lever hinged to said ears and having longitudinally arranged depending flanges bearing against the movable jaw.
3. A flexible tubing compressor comprising a sheet metal body portion developed into fixed and movable jaws, the fixed jaw having uprising ears, and a compressing lever hinged to said ears and having longitudinally arranged depending flanges bearing against the movable jaw, the lever being so hinged to the ears with respect to the bearing points of said flanges as to yield slightly when the lever is swung to close the jaws.
4. A flexible tubing compressor comprising a sheet metal body portion developed into fixed and movable jaws, the fixed jaw having uprising ears, and a compressing lever hinged to said ears and having longitudinally arranged depending flanges bearing against the movable jaw, the lever being developed into a loop between the flanges and the hinged connection to permit the lever to yield slightly when swung to close the jaws.
5. A flexible tubing compressor comprising a sheet metal body portion developed

into fixed and movable jaws, the fixed jaw having uprising ears, and a compressing lever hinged to said ears and having longitudinally arranged depending flanges bearing against the movable jaw, the movable jaw having longitudinally arranged stiffening ribs forming grooves for guiding the bearing points of the flanges in their travel along the jaw.

6. A flexible tubing compressor comprising a sheet metal body portion developed into fixed and movable jaws, the fixed jaw having uprising ears, and a compressing lever hinged to said ears and having longitudinally arranged depending flanges bearing against the movable jaw, the movable jaw having longitudinally arranged stiffening ribs forming grooves for guiding the bearing points of the flanges in their travel along the jaw, the fixed jaw having stiffening ribs at the base of the ears opposite the bearing points of the said flanges.

7. A flexible tubing compressor comprising a sheet metal body portion developed into fixed and movable jaws, the fixed jaw having uprising ears, and a compressing lever hinged to said ears and having longitudinally arranged depending flanges bearing against the movable jaw, the front edges of the uprising ears being recessed to give additional room for lateral displacement of the flexible tubing when the tubing is compressed by the closure of the jaws.

In testimony, that I claim the foregoing as my invention, I have signed my name this 26th day of January, 1920.

AUGUST J. FREY.
